UNITED STATES PATENT OFFICE

ADOLF WELTER, OF KREFELD-RHEINHAFEN, GERMANY

COMPRESSED AIR SOAP

Original application filed May 2, 1929, Serial No. 360,093, and in Germany October 31, 1928. Divided and this application filed October 17, 1930. Serial No. 489,465.

The present invention relates to an improved process for preparing soap powder from liquid grain soap.

It has hitherto been usual to produce soap powder from liquid grain soap by heating the latter in a closed vessel (autoclave) to a temperature exceeding 100° C., and then supplying the liquid grain soap under the pressure prevailing in the vessel to any atomizing apparatus. Naturally, the soap solution is the more thinly liquid and, accordingly, the atomization is the better, the higher the pressure prevailing in the vessel and therefore the temperature producing it. In order to secure these favourable conditions as much as possible, steam for example has been injected into the pressure vessel. However, the soap solution was so much diluted by this that the atomization was not effected advantageously. Again, instead of injecting steam, the vessel containing the liquid grain soap has been heated by means of heating devices from the exterior, i. e. by heating devices from which no steam could enter the vessel. However, the soap on the walls of the vessel then became so strongly heated, that solid masses (incrustations) set on the walls, which masses acted, so to speak, as heat insulators, and caused considerable waste of heat. This became very apparent, and was very disadvantageous particularly when filled soaps, i. e. soaps mixed with other additions such as, for example, water-glass, were treated.

A further disadvantage also was that only large vessels could be used for working in, since only then could a uniform pressure be ensured, which is necessary for a good atomization. In this case, however, too great a space remains free over that part of the vessel filled with liquid, into which too much steam could escape from the liquid contents of the vessel. This loss of steam concentrated the liquid too much, so that its drying up and therefore the formation of incrustations was very much favoured. On the other hand explosions were readily caused by these incrustations.

It has now been found that soap powder may be produced by the direct atomization of liquid grain soap easily and advantageously,

i. e. without too great an expenditure of heat, if the process is carried out so that no appreciable quantities of solid material can deposit on the inner walls of the pressure vessel during the heating of the grain soap in the latter vessel. More particularly filled soaps may be advantageously treated in this way. By "filled soap" is meant any soap containing one or several of the fillers known in the art, e. g. water-glass, soda, potash, salts of phosphoric acid, clay, fuller's earth, etc.

As means for preventing solid material from setting on the walls of the vessel, the injection of steam as highly compressed and as superheated as possible into that part of the vessel space above the liquid during the heating of the contents of the vessel to a temperature exceeding 100° C., serves pre- 65 eminently. Further, the amount of water which condenses from the steam under these 70 conditions is not large enough to dilute the soap lye too much.

It is better so to proceed, however, that, preferably using heating devices from which no steam enters the vessel, a non-condensable 75 gas, e. g. usually air, is injected into the part of the vessel space above the liquid during the heating of the contents of the vessel to a temperature exceeding 100° C. This air must be at a pressure which exceeds that corre- 80 sponding to the temperature of the soap lye heated in the vessel. The air need not be preliminarily heated, and therefore no costs are entailed in this respect. The space over 85 the liquid filled with gas or steam should be kept as small as possible, so that only a very small amount of air need be used. By this means the rise in temperature will take place in a much shorter time and no incrustations will be formed on the interior walls of 90 the vessel.

Examples

1. Liquid, pure grain soap with a fatty acid content of 60-64%, contained in a closed vessel, is heated from the outside by means of a steam jacket to a temperature of 175° C., superheated steam at 10 to 14 atmospheres being simultaneously forced in the space above 95 the soap, so that the pressure in the vessel 100

is always 3-4 atmospheres higher than the vapour pressure corresponding to the temperature of the vessel. The liquid soap is then led to known atomization apparatus under the pressure prevailing in the vessel.

2. The process is carried out as in Example 1, only the pressure vessel is heated by direct firing and a stirring device is allowed to rotate in the mass.

10 3. The process is carried out as in Example 1 or 2, only that, instead of superheated steam, compressed air at 10-20 atmospheres is blown in.

4. The process is carried out as in Example 1, 2 or 3, only that, in place of pure grain soap, a grain soap is used which contains 10% water-glass and 5% soda.

I do not intend to limit myself in any way whatsoever to the details mentioned in the foregoing description and examples with regard to the methods of working, the temperatures, pressures, mixtures, heating devices, etc. Every working procedure and accessory thereto, in which soap powder is prepared from liquid grain soap, more particularly from filled grain soap, in such a way that the grain soap is heated in a closed vessel to a temperature above 100° C. with employment of the said means for preventing solid masses or crusts from setting on the walls of the vessel during the said heating, and the thinly liquid grain soap, while still hot, is then supplied to an atomizing device by the pressure prevailing in the vessel and is thus converted, by means of a known atomization process, into soap powder is to be regarded as coming within the scope of the present invention. In this way a dry non-caking powder is formed against an opposed current of air by means of any atomization apparatus; the air current need be only comparatively weak and, also need not be warmed. Since the heat content necessary for vapourizing the water contained in the atomized soap is, in the process which is the subject of the present invention, already present in the hot soap mass to be atomized, it is not necessary, therefore, to supply it separately.

50 More particularly is it to be remarked, that the heating of the pressure vessel may be produced by any means, e. g. from the exterior by direct firing, by an oil or metal-bath, by a steam jacket, by tubes enclosed in or welded on the walls (on the casing) heated by steam, hot water under pressure, or hot oil. Also heating elements of any kind may be built or suspended within the vessel in the liquid. Also, in order to improve the heat distribution, a stirring mechanism of any kind may be arranged in any manner.

In the accompanying drawing, an apparatus suitable for carrying out the present invention is shown schematically by way of example. In this drawing 1 is a pressure ves-

sel provided with an inner upright shaft 2 for the stirring mechanism 3. The mechanism for actuating the stirrer is denoted by 4. 5 is a device for introducing liquid soap, 6 is a de-aerating cock, 7 is the outlet cock, 8 is the steam jacket, 9 is the pipe for the fresh steam and 10 is the wastepipe for the water of condensation.

I do not limit myself in any way to the use of an apparatus which corresponds exactly to that shown in the accompanying drawing, but the apparatus may be modified as desired within the scope of the object of the invention.

What I claim is:

1. A process for producing soap powder from liquid soap which comprises heating liquid soap in an enclosed space to a temperature exceeding 100° C., simultaneously injecting a gaseous fluid into the portion of the enclosed space above the liquid soap, and then atomizing the liquid soap under the pressure prevailing in the enclosed space.

2. A process for producing soap powder from liquid soap which comprises heating liquid soap in an enclosed space to a temperature exceeding 100° C., simultaneously injecting a non-condensable gas into the portion of the enclosed space above the liquid soap, and then atomizing the liquid soap under the pressure prevailing in the enclosed space.

3. A process for producing soap powder from liquid soap which comprises heating liquid soap in an enclosed space to a temperature exceeding 100° C., simultaneously injecting a non-condensable gas into the portion of the enclosed space above the liquid soap, and then atomizing the liquid soap under the pressure prevailing in the enclosed space.

4. A process for producing soap powder from liquid soap which comprises heating liquid grain soap in an enclosed space to a temperature exceeding 100° C., simultaneously injecting compressed superheated steam into the portion of the enclosed space above the liquid soap, and then atomizing the liquid soap under the pressure prevailing in the enclosed space.

5. A process for producing soap powder from liquid soap which comprises heating liquid soap in an enclosed space to a temperature exceeding 100° C., simultaneously injecting air into the portion of the enclosed space above the liquid soap, and then atomizing the liquid soap under the pressure prevailing in the enclosed space.

In testimony whereof I have signed my name to this specification.

ADOLF WELTER.
